(57) **CLAIM**

The ornamental design for a foldable bag, as shown and described.

DESCRIPTION

FIG. 1 is a first perspective view of a foldable bag showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the foldable bag thereof; and,

FIG. 10 is an enlargement view of the foldable bag shown in FIG. 1.

The dash-dash broken lines shown in the drawings depict portions of the foldable bag that form no part of the claimed design. The long dash dash broken lines in FIGS. 1 and 10 depict boundary lines of an enlargement that form no part of the claimed design.
